UNITED STATES PATENT OFFICE.

CRAWFORD P. McGINNIS AND CHARLES W. DAKE, OF CHICAGO, ILLINOIS, ASSIGNEES
TO THE PYLE-NATIONAL COMPANY, OF CHICAGO, ILLINOIS, A CORPORATION OF
NEW JERSEY.

LOCOMOTIVE HEADLIGHT AND MOUNTING THEREFOR.

Application filed January 7, 1926. Serial No. 79,733.

The invention relates to improvements in locomotive headlights and mounting therefor and has for one object to provide a new and improved type of headlight mounting where-
5 in the casting line of the beam projected by the headlight may be easily and conveniently adjusted. Another object of the invention is to provide a device wherein the combined headlight housing may be brought
10 together in a satisfactory manner for adjustment and operation. Another object will be to provide a housing particularly well adapted to contain both a headlight bulb and a pilot light bulb in one assembly.
15 Other objects will appear from time to time in the course of the specification and claims.

This invention is illustrated more or less diagrammatically in the accompanying drawings, wherein—

20 Figure 1 is a longitudinal section on a vertical plane through the headlight base and housing;

Figure 2 is a front elevation with parts removed;

25 Figure 3 is a side elevation;

Figure 4 is a section on an enlarged scale through the light bracket;

Figure 5 is a section along the line 5—5 of Figure 4.

30 Like parts are indicated by like characters throughout the specification and drawings.

A is a headlight base. It comprises a box having a plurality of lugs A¹ A² adapted to be fastened to any suitable supporting platform upon which the headlight can be mounted. This box may contain a light source A³ and has at either side the outwardly and rearwardly inclined translucent door panels A⁴ A⁴ held in place to close the box by means 40 of links A⁵ and thumb screws A⁶. These panels are extended by pivot hinges A⁷ so that access may be had to the interior of the box to replace the light source and to place number plates on the inside of the translucent panel so that the engine number can be illuminated and easily read. The forward top portion of this box is bounded by a generally parabolic wall A⁹ and provides clearance by the headlight housing 45 itself.

The headlight housing comprises a metal bell B generally parabolic and terminating at the front in a cylindrical sleeve B¹ slightly offset or enlarged from the bell as in-

dicated. Projecting outwardly from this 55 cylinder B¹ are lugs B² B² in which are threaded cap screws B³. These cap screws engage longitudinally disposed horizontal slots B⁴ in lugs B⁵ projecting upwardly from the base A so that the front end of 60 the housing is supported in these lugs. At the rear extremity of the bell B is an outwardly and rearwardly inclined lug B⁶ apertured at B⁷ and adapted to engage the downwardly and rearwardly inclined surface of a lug B⁸ projecting upwardly from the box A. A cap screw B⁹ is threaded in the lug B⁸ passed through the aperture B⁷ which is considerably larger than the cap screw and carries a washer B¹⁰ interposed between 70 the head of the cap screw and the lug B⁶.

C is the reflector contained within the bell B and out of contact except around its outer periphery where a cushion C¹ is provided. C² is a holding ring having cushioning elements C³ engaging the edge of the reflector. This holding ring is held in place by a sleeve C⁴ carried by brackets C⁴⁰ inside the member B¹ to hold the reflector in place. Projecting inwardly from the ring 75 C⁴ are a plurality of supporting strips C⁵ and a hollow supporting arm C⁶. The arm and strips support a fixed sleeve C⁷ in which is slidably mounted a threaded adjusting sleeve C⁸. This sleeve is slotted at C⁹ to engage a pin C¹⁰ in the sleeve C⁷ to hold the adjusting sleeve against rotation. Nuts C¹¹ C¹² engage the threaded surface of the adjusting sleeve C⁸ and abut against the ends of the sleeve C⁷ so that by adjusting of these 85 nuts the sleeve may be moved longitudinally, the pin holding it against rotation while permitting its longitudinal movement. The fixed sleeve C⁷ and the adjusting sleeve C⁸ are apertured at C¹³ in line with the hol- 90 low leg or arm C⁶.

Mounted in either end of the adjusting sleeve C⁸ are electric light sockets D D¹ in which are mounted electric light bulbs D² D³. Wires D⁴ D⁴ lead up through the hollow arm C⁶ and aperture C¹³ into the interior of the sleeves C⁷ C⁸, some of them going to the socket D and others to the socket D¹. These wires have their other ends pass down through the aperture D⁵ in the ring C⁴ and out through the thimbles D⁶ in the lugs D⁷, which project upwardly 100 from the lower portion of the top of the 105

housing A, thus the wires pass down to the binding post D⁸. It will be noted that the member B¹ is apertured at D⁹ to permit the thimbles D⁶ and lugs D⁷ to interlock 5 with it thereby avoiding interference when the headlight is being adjusted and at the same time giving a certain amount of closure to the headlight housing, there being only sufficient space left between the aperture in the ring and the lugs to permit ventilation of the housing.

E is a visor ring mounted on the ring B¹ projecting forwardly therefrom. Its upper portion is wider than its lower and it is 15 closed by a concave glass or translucent window E¹ having a reinforcing ring E² where the glass engages the visor and held in position by means of the clamp springs E³ and screws E⁴ working in opposition between a 20 flange E⁵ and lug E⁶ whereby the housing is closed at the front against the elements.

The visor E is pivoted on the hinges E⁷ projecting from the member B¹ and is adapted to be held in the closed position by 25 means of the hook E⁸ engaging a pin E⁹. E¹⁰ is a compressible packing interposed between the visor frame and the balance of the housing.

It will be evident that while we have 30 shown in our drawings an operative device, still many changes might be made in the size, shape and disposition of parts without departing materially from the spirit of our invention and we wish, therefore, that 35 our showing be taken as in a sense diagrammatic.

The use and operation of this invention are as follows:

The box frame or headlight base is 40 mounted on any suitable platform, bracket or other support on the locomotive and bolted firmly in position thereon being arranged with its longitudinal axis generally in line with the locomotive axis.

45 The reflector housing being mounted on the box frame by means of three lugs, one at each side and one at the rear, may be when the holding screws are loosened adjusted with respect to the box frame so that 50 the axis of beam projected by the reflector will be in a vertical plane containing the axis of the locomotive and because the rear lug is downwardly and rearwardly inclined and engages an inclined abutment the angle 55 made by the axis of the beam and the horizontal may be adjusted to control the point at which the beam intersects the ground, this being made possible because the aperture in the rear lug through which the rear set 60 screw penetrates is a large, round aperture permitting adjustment within limitation in any direction. The apertures in the lugs projecting up from either side of the box frame and engaging the cap screws and the 65 reflector housing being elongated in a hori-

zontal plane permit angular adjustment of the reflector housing in a horizontal plane only, the adjustment of the vertical plane being as above noted made at the rear end.

The wires carrying the current to the 70 light source or sources in the reflector housing pass up through the box frame and through the sleeve there shown which penetrates within the enlarged aperture in the 75 lower central portion of the reflector housing. The space between the sleeve and the wall of the aperture is sufficient to permit adjustment without binding. Therefore, space would have to be left open to permit condensation, sweating and the like to 80 escape from the reflector housing.

Since there is a three point support for the reflector housing, the range of movement in the two forward side supports permits angular movement of the axis of the reflector 85 housing in a horizontal plane whereas the inclined surface upon which the lug at the back of the reflector housing permits also angular movement in a vertical plane, thus a universal movement can be made by loosening 90 the three holding cap screws and slightly moving the reflector housing into position and then tightening the screws.

We claim:

1. In a headlight for locomotives and the 95 like, a base frame, three spaced lugs thereon, two of them horizontally slotted, the other having an inclined plane surface, a headlight housing mounted on the frame, lugs thereon in opposition to the lugs on the 100 frame, screws in two of said lugs passing through the slots on the lugs on the frames, the other lug inclined to engage the inclined lug on the frame and having a large hole therein, the screw on the frame passing 105 therethrough.

2. In a headlight for locomotives and the 110 like, a base frame, three spaced lugs thereon, two of them horizontally slotted, the other having an inclined plane surface, a headlight housing mounted on the frame, lugs thereon in opposition to the lugs on the 115 frame, screws in two of said lugs passing through the slots on the lugs on the frame, the other lug inclined to engage the inclined lug on the frame and having a large hole therein, the screw on the frame passing 120 therethrough, the lugs on the headlight housing being all of them located just below the horizontal axial plane of the reflector.

3. A headlight for locomotives and the 125 like comprising a box supporting frame, the front and top walls being cut away to form a concave cradle, a headlight housing projecting upwardly from the box frame and penetrating within said cradle but out of contact with the walls thereof and means for holding the housing and frame in operating relation, registering apertures in 130

the box frame and the housing, electric conductors extending through the box frames and said apertures into the housing, a sleeve surrounding the aperture on the box frame and projecting upwardly into the headlight housing through the aperture therein.
